KILN AND METHOD OF FIRING THE SAME

Edwin E. Slick, Pittsburgh, Pa.

Application December 14, 1946, Serial No. 716,366

7 Claims. (Cl. 25—151)

1

This invention pertains primarily to the burning of refractory shapes in kilns, as for example the burning of refractory blocks and bricks, but is applicable also to various other kilns and in fact to other operations using coal burning equipment.

A conventional kiln for the burning of brick is circular in construction with a dome-shaped top, and it has a number of coal burning units at regular intervals around it with firing doors and ash removal doors for each unit. While hand-fired grates are the most common arrangement, it has been proposed to use mechanical stokers of conventional type in which the coal is forced up through a central passage or retort and as it burns, the ash is clinkered and the clinkers removed from time to time.

Many types of ceramic or refractory articles are extremely sensitive to temperature changes during burning. Silica brick, for example, is fired at a temperature of around 2700° F. and the temperature must be gradually and uniformly increased to avoid damage.

With hand firing of coal burners the attendant is very likely to let the fires burn down, then throw in a quantity of fuel, resulting in uneven firing and the opening of the doors for throwing in coal and removing ash admits cold air that is detrimental. Not infrequently as much as 10% of the ware in the kiln is damaged by uneven firing, and a high percentage of loss is always expected.

While conventional stokers tend to keep a more uniform rate of combustion the ash is accumulated in the fire pot and is converted into a clinker. The operator must frequently open the fire door and remove these clinkers. During this operation, air enters through the fire door, tending to reduce the temperature, thus detrimentally affecting the burning of the ware.

According to the present invention there is provided a stoker arrangement wherein the ash is continuously forced from the fire pot or combustion zone as it is produced, where it falls into a pit in which it may accumulate during the entire period of the operation of the firing of the kiln, or at least during that period of the firing which is critical, so that it is unnecessary to open the firing door at any time after the fires have been started, nor is it necessary to open the ash door. Thereby it becomes possible to uniformly increase the temperature within the kiln and avoid damage to the ware, due to any sudden variation or dropping of the temperature in any particular

part of the kiln and the labor and skill required of the attendant is greatly reduced.

In the arrangement contemplated by the present invention the kiln is provided with a number of similar stokers more or less equally spaced around the side of the kiln. The coal feeds uniformly and continuously into each stoker moving radially toward the center of the furnace, and as it moves combustion takes place. At the inner end of the stoker unit the coal will have been converted to ash and the ash drops out of the stoker into the ash pit where it may accumulate for a considerable period of time.

While the stoker has been especially designed for use in a brick burning kiln, it is also applicable to other operations where it is desired to automatically stoke and effect removal of the ashes from the fire-pot without manual attention.

My invention may be more fully understood by reference to the accompanying drawings, in which:

Fig. 1 is a top plan view of one more or less conventional form of kiln having my stokers applied thereto, only a part of the furnace which is symmetrical being shown, on account of the size of such furnace;

Fig. 2 is a side elevation of a portion of the furnace shown in Fig. 1;

Fig. 3 is a fragmentary section through the wall of the kiln showing one of the stokers partly in side elevation and partly in section, the view being on a larger scale than Figs. 1 and 2;

Fig. 4 is a horizontal section in the plane of line IV—IV of Fig. 3;

Fig. 5 shows the apparatus disclosed in Fig. 3 in an end elevation; and

Fig. 6 is a fragmentary transverse section through the fire-pot, the view being substantially in the plane of line VI—VI of Fig. 3.

Referring to the drawings there is shown a more or less conventional form of kiln, which kiln is completely circular as is well understood by those skilled in the art, and has a side wall 2 and a dome-shaped top 3. One or more entrance doors are provided in the side at 4. The stoker units are designated generally as 5 and they are disposed at regular intervals around the periphery of the kiln with their longitudinal axes radial to the kiln.

As more clearly shown in Figs. 3, 4, 5 and 6, the stokers are provided with a feed hopper 6 which delivers coal into a screw conveyor 7 that extends horizontally beneath the hopper. A motor 8 drives a shaft 9, which in turn has a worm thereon for engaging a worm wheel 10 for turning

the conveyor screw 11. The shaft 9 also drives a blower fan (not shown) but which is of conventional form, and which is contained within a fan housing 12 alongside the gear box for the screw conveyor drive.

The fan housing has an intake opening 13 and delivers air into a duct 14 that extends along one side of the screw conveyor tube 7 as most clearly shown in Fig. 4. Both the screw conveyor and the duct pass through the wall 2 of the kiln.

The inner end of the screw conveyor tube opens into a trough-shaped retort or a fire-pot designated generally as 15 and which, as shown in Fig. 5, extends radially inwardly. This retort or fire-box is shown in Fig. 6 as having a rounded bottom 16 with upwardly diverging sides 17, these sides merging into outwardly-turned rim portions 18. A sheet metal casing 19 extends downwardly from the edges of the rim 18 and under the bottom of the trough forming a wind box 20 into which the air duct 14 opens.

As best shown in Fig. 3, the top edge of the retort or fire-pot slopes downwardly and inwardly while the innermost part of the bottom of the trough 16 extends inwardly and upwardly, there being a somewhat rounded end wall portion 21 at the inner end of the trough. The sheet metal casing 19 also joins the downwardly-turned flange 21' at the outer edge of this rim for closing the wind box. The upwardly sloping portion of the bottom 16 is designated 16' (see Fig. 3).

The side rims 18 at each side of the trough and the end rim portion 21 are provided with numerous openings that direct currents of air inwardly and upwardly toward the mid plane of the trough, these openings providing the combustion air for burning the fuel. The rim of the fire-pot thus constitutes a tuyère.

In operation the screw delivers coal into the trough. The coal moves radially inwardly and upwardly filling the trough and combustion takes place continuously along the rim which forms the tuyère for supplying the combustion air. There is progressive movement of the whole body of coal inwardly and the rate of feed is so adjusted to the rate of combustion and the length of the trough that by the time the coal reaches the inner end 21 of the retort or combustion chamber it will have been substantially entirely reduced to ash. This ash falls downwardly in the space between the skirt 21 forming the end of the stoker unit and the bag wall 22 of the kiln. The stoker is supported on bars 23 which are commonly provided at the present time in kilns, and below the bars 23 there is a large ash pit 24 or other ash receiver which extends from the outer vertical wall inwardly toward the bag wall 22.

As best seen in Fig. 5, there are two ash doors 26 opening into the ash pit, one at each side of the mid plane of the stoker which seal it against free inflow of outside air. Likewise there are two firing doors 27, one being at each side of the fuel hopper and affording access to the combustion unit. All these doors are normally closed during operation.

As best shown in Figs. 4 and 6, there is brick work 28 sloping upwardly and outwardly from the tops of the tuyères for preventing fuel from overflowing at the sides of the retort and allowing the burning fuel to spread out to a limited extent.

All of the stoker units are the same and while I have shown one particular form of drive for

the screw feeds of the stokers, it will be understood that this is merely by way of illustration, and that various other drives for the screw feeds may be provided. Ordinarily in an operation

5 of this kind the stoker operates more or less continuously and the rate of feed and the rate at which the fuel bed is moved is coordinated to the length of the trough (and also the rate of combustion) to assure substantial consumption 10 of the fuel before it reaches the discharge end. This is simply obtained by a proper adjustment of the feed of the screw or of the speed of the motor which drives it. Each of the stokers provides an elevated trough-shaped retort or fire pot 15 that extends radially inwardly so that in the operation of the kiln there is at each station an inwardly progressing burning bed of fuel which, by the time it reaches the innermost end of the retort, has been substantially reduced to ash, 20 and which before any substantial clinkering takes place, discharges freely into the large ash pit or ash receiver provided under the stoker. This arrangement enables substantially uniform conditions of combustion to be maintained at 25 each firing station and uniform rates of combustion to be maintained, and the operation of firing can take place after the kiln is started without there normally being any need for opening the fire doors or the ash removal doors.

30 Hence ceramic articles, and particularly articles such as silica brick which are very sensitive during firing to any heat changes, can be burned with not only a considerable economy of fuel, but with considerably less loss due to temperature changes. The ash discharges beyond the zone of combustion so that any dust that may be formed by the falling ash is in a quiescent atmosphere and is not carried into the furnace.

40 As hereinbefore indicated, while the stoker has special adaptation to a kiln of the class described, it is also applicable to other arrangements where coal is to be burned and the ash is to be automatically discharged.

45 While I have illustrated and described one specific embodiment of my invention, it will be understood that this is by way of illustration and that various changes and modifications may be made therein.

50 I claim:

1. A kiln for the burning of products to be fired comprising a kiln structure having side walls and a roof, and a plurality of stokers around the side walls of the kiln, each stoker being 55 constructed to move a burning body of fuel at a controlled rate inwardly toward the center of the kiln and discharge the ash at the end remote from the side wall.

2. A kiln for the burning of products to be 60 fired comprising a kiln structure having side walls and a roof, and a plurality of stokers around the side walls of the kiln, each stoker being constructed to move a burning body of fuel at a controlled rate inwardly toward the center of

65 the kiln and discharge the ash at the end remote from the side wall, the kiln having an ash pit therein under the stoker for holding an accumulation of ashes so discharged, said ash pit being closed against free circulation of air there-

70 through, each stoker having means for delivering air to the fuel bed under positive pressure.

3. A kiln for the burning of products to be 75 fired comprising a kiln structure having side walls and a roof, and stoker means at a plurality of stations around the wall of the kiln,

said stokers operating to move the fuel as it burns inwardly at a controlled rate toward the center of the kiln and discharge the resulting ash at the inner end of the stoker, there being an ash compartment under each stoker into which the ash is discharged and which is normally closed against free ingress of outside air.

4. A kiln for burning ceramic and like articles comprising a circular structure having a plurality of stokers around its periphery, each stoker being provided with an inwardly elongated fire pot whereby the burning coal moves progressively as it burns radially of the structure and discharges at the inner end thereof, each stoker having means for advancing the burning fuel along the elongated fire pot at a controlled rate, and means for supplying air to the fire-pot.

5. A kiln for burning ceramic and like articles comprising a circular structure having a plurality of stokers around its periphery, each stoker being provided with an inwardly elongated fire pot whereby the burning coal moves progressively as it burns radially of the structure and discharges at the inner end thereof, the fire-pot having an end wall to retard the free movement of fuel along the fire-pot and maintain the fuel bed at a controlled depth, the ash being discharged over the end wall, each stoker having means for effecting the movement of the fuel bed at a controlled rate along the fire-pot, and an ash receiver normally closed against ingress of outside air into which the ashes fall from the inner end of the stoker, the stoker having means for supplying air along the fire-pot to the fuel.

6. A kiln for burning ceramic and like articles comprising a circular structure having a plurality of stokers around its periphery, an ash pit under each stoker, each ash pit having an

ash door for removal of ashes therefrom, each stoker being designed to progressively move coal as it burns at a controlled rate radially of the structure and discharge the ash into the ash pit, there being a passageway at the inner end of each stoker opening vertically into the firepit, said passageway being inwardly of the combustion zone and the ash pit being air-tight whereby a counter flow of air to float fine ash upwardly through the passageway is avoided.

7. The method of firing a coal-fired kiln which comprises progressively advancing the coal while it is burning from several stations around the periphery of the kiln toward the center at a controlled rate, dropping the resulting ash at the end of its travel into an ash receiver which is normally closed against the free inflow of outside air whereby firing temperature in the kiln may be uniformly reached and opening of the kiln during firing avoided.
